CLAIM

The ornamental design for a crushing machine for attaching to tractors, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a crushing machine for attaching to tractors according to my design;

FIG. 2 is a left view thereof;

FIG. 3 is a perspective view thereof;

FIG. 4 is a top view thereof;

FIG. 5 is a right view thereof;

FIG. 6 is a bottom view thereof; and,

FIG. 7 is a back view thereof.
